DISPLAY RACK

George B. Kurtzon, Chicago, Ill., assignor to Garden City Plating & Manufacturing Co., a corporation of Illinois

Application August 25, 1949, Serial No. 112,279

4 Claims. (Cl. 211—94)

This invention relates to a clothing display rack. In particular it relates to a parallel bar rack having means to control the rotation of the rack so that clothing supported by the rack may be selectively displayed.

Racks of this general type have been used for many years in displaying clothing, such as suits, overcoats and dresses, and ordinarily comprise a centrally disposed standard mounted on a floor-supported platform in such a manner that it may be moved relative to the platform to move the parallel bars closer to the customer. The rack may then be rotated so that the clothes supported on either bar may be closely inspected by the customer. These racks may be contained in a glass walled show case, or they may be installed in any other desired place in a store or show room.

Some of the principal objections to the prior art clothing racks of the type referred to, which the present invention is designed to overcome, are the heavy, expensive structure of the centrally disposed standard and the slow and cumbersome manipulation of the rack necessary in order to display the merchandise supported thereon.

In a display rack constructed in accordance with the present invention the centrally disposed standard and the floor-supported platform are eliminated, and the rack is supported by a rectangular frame that may be mounted in the top of a show case, or it may be supported either from a wall or the ceiling of the store or show room. In either case the total weight of the device is substantially reduced and the manipulation thereof is greatly simplified and made more facile.

The present invention contemplates an inclined guide with suitable latch means to hold the rack normally in its rearmost position, means readily operable for releasing the latch so that the rack may glide forwardly to display position by force of gravity, and efficient means to stop the forward motion of the rack without appreciable noise or shock when the rack reaches its foremost position.

The display rack may be rotated only when it is in its foremost position, and cam means is provided for bringing the rack to rest in a predetermined position when it is rotated.

The structure by which the above and other advantages of the present invention are attained will be described in the following description, taken in conjunction with the accompanying drawings of some preferred illustrative embodiments thereof, in which:

Figure 1 is a perspective view of a display rack embodying the invention;

Fig. 2 is a longitudinal sectional view through the rack taken along the line 2—2 of Fig. 1, the full lines showing the rack in the forward position and the dotted lines in the normal rearmost position;

Fig. 3 is a top elevational view of the rack, showing the rack in the forward position;

Fig. 4 is an end elevational view, looking from the left

2

of Fig. 3, showing the rack rotated through 90° in dotted lines;

Fig. 5 is a cross sectional view, taken along the line 5—5 of Fig. 3;

Fig. 6 is a detail perspective view of the cam which stops the rotary motion of the rack;

Fig. 7 is a fragmentary perspective view showing a modified brake means for stopping or assisting in the stopping of the forward movement of the rack;

Fig. 8 is a modified embodiment of the rack showing different means for controlling the forward and rearward movement of the rack; and

Fig. 9 is a fragmentary side elevation of another modified embodiment showing still different means for controlling the forward and rearward movement of the rack.

In the drawings, the reference numeral 2 indicates a rectangular frame comprising longitudinal channel irons 3 and 4, and transverse end members 5 and 6. The longitudinal channel irons are positioned on their sides with their open ends facing each other for a purpose herein-after described.

The frame may be supported by means of end brackets 7 secured to a suitable wall surface, or by rods or chains 8 depending from the ceiling, or by a combination of both. If the rack is to be mounted in a display case it may be supported by the top of the case in any suitable manner. In the preferred embodiment of the invention, the front end 5 of the frame is positioned slightly lower than the rear end 6 so that the longitudinal channel irons are inclined downwardly towards the front end.

The garment carrier or rack comprises a pair of spaced parallel bars 9 adapted to support a plurality of individual garment hangers (not shown) upon which the garments to be displayed are hung. The ends of the

parallel bars as tied together by curved metal strips 10 which abut the garments hung at the ends of the bars to confine them within the limits of the bars. Intermediate their ends the parallel bars are supported by a plurality of arms 11, the inner portions of which are rigidly secured to a collar 12 rigidly mounted on the lower end of a shaft 13 and held by a pin 12'. Arms 11 may be braced by means of reinforcing bars 11'.

A plate 14 apertured at a central hub portion, as indicated at 15, to receive the top end of shaft 13, is supported by two cross members 16 and 17. Rollers 18 are rotatably mounted on each end of each of cross members 16 and 17. The rollers ride along the inner surfaces of the longitudinal channel irons 3 and 4 which serve as tracks. A pair of wedge shaped strips 3' and 4' mounted on the inner surface of channel irons 3 and 4 adjacent their front ends provides a surface inclined upwardly slightly at the front of the frame to arrest the forward movement of the garment carrier as it approaches its foremost position. A cam 19 supported on plate 14 is also apertured, as indicated at 19', to receive the top end of shaft 13. Shaft 13 is projected through the apertures in plate 14 and the cam, and a pin 20 is passed through a transverse aperture 20' in shaft 13 above the cam. Both ends of pin 20 extend on opposite sides of the shaft, and rollers 21 are mounted on each end of the pin so that the weight of the garment carrier holds shaft 13 down with rollers 21 engaging the surface of cam 19.

As shown in Fig. 6, the surface of cam 19 has two radial grooves 22 aligned with each other and defining the lowermost level or trough of the cam surface. When the garment carrier is rotated to display garments simultaneously on both parallel bars (which is the normal display position) it is not necessary to hold the carrier in any particular position because the weight of the garment carrier will cause rollers 21 to come to rest in grooves 22. These grooves form a stable rest position for the rollers because they are lower than any other

portion of the cam surface. The position of grooves 22 in the surface of the cam is fixed so that the carrier will be in the desired display position when rollers 21 come to rest in the grooves.

Another pair of grooves 23 is provided in a higher plane of the cam at right angles to grooves 22. Grooves 23 serve to provide a temporary rest for rollers 21 if it is desired to hold the parallel bars at right angles to their normal display position. If excessive force is applied to the garment carrier to spin it around, grooves 23 serve as means to help slow the rotation of the carrier so that it will come to rest quicker than if grooves 22 were the only grooves provided in the cam surface.

In order to prevent rotation of the garment carrier except when it is at the forward end of frame 2, a rod 24, shorter than the length of frame 2, is disposed centrally of the frame and extends parallel to longitudinal channel members 3 and 4. Rod 24 is supported at its ends by cross-members 25 and 26 which are in turn supported by the longitudinal channel members. Cross member 25, and hence the end of rod 24 supported thereby, is spaced rearwardly of front end member 5 a distance slightly greater than the distance between member 5 and the rearmost extremity of shaft 13 when the garment carrier is in its foremost position. The upper end of shaft 13 is provided with a slot 27 into which rod 24 fits. When rod 24 is engaged with the slot it is impossible for the shaft to be rotated, and therefore the garment carrier can not be turned. When the garment carrier is moved to its foremost position, as shown in Fig. 1, the slot is clear of rod 24 and the garment carrier may be rotated. Although the rod is shown as being rectangular in cross section, it may be circular or of any other desired shape.

A latch member 28 normally holds the garment carrier in its rearmost position. Any suitable latch mechanism may be used, and such mechanism may be manually or electrically operated. In Fig. 1, there is shown a conventional electrically operated solenoid which normally holds the core, as shown in the form of a bolt 29, projecting downwardly. A latch 30 is mounted on cross member 17. The latch is provided with an aperture 31 which normally engages bolt 29 to hold the garment carrier in its rearmost position. The free end of latch 30 is provided with a downwardly inclined lip 32 which engages the bolt when the garment carrier is moved to its rearmost position and forces the bolt upwardly until the bolt registers vertically with aperture 31 into which it then drops by gravity. When the garment carrier is in its rearmost position and is to be moved forwardly, a suitable push button (not shown) is pressed to close the electrical circuit and thus energize the solenoid to raise the bolt, and gravity causes the garment carrier to glide forwardly because of the inclination of channel irons 3 and 4.

In the preferred embodiment of the invention suitable cushioning means is provided to arrest the forward movement of the garment carrier as it approaches its foremost position. The cushioning means may comprise a plurality of spring pressed bumpers or bumpers having hydraulic cylinders to absorb the shock, but I prefer to use the cushioning means shown in Fig. 1. Thus, as shown in Fig. 1, a bar magnet 33, preferably of the permanent type, is mounted in the front end of frame 2 and another similar bar magnet 34 is mounted on the front of cross member 16. The magnets are arranged with their like poles facing each other so that as magnet 34 approaches magnet 33 the repellent force tending to push the magnets apart arrests the forward motion of plate 14. The weight of the garment carrier supported on plate 14 is great enough to cause gravity to overcome the repellent magnetic force, but the magnetic force will cushion the stopping of the forward motion. It will, of course, be understood that the magnets used to accomplish this will vary in size, dependent on the weight of the garment.

carrier and the slope of the frame in which the garment carrier rides. When the garment carrier is pushed rearwardly, the magnetic force will add its power to the force starting the garment carrier in its movement towards its rearmost position.

In Fig. 7 a different means is shown for cushioning the stopping of the forward movement of the garment carrier. In this embodiment a metal plate 35 is secured to channel iron 3 adjacent its front end and has a resilient flange 36 bent inwardly to engage the flat surface of roller 18. Flange 36 may be flared towards channel iron 3 to bring the forward motion of the garment carrier to a complete stop, or may merely arrest its forward movement to cushion the shock of stopping. If desired, a duplicate of plate 35 may be secured also to channel iron 4.

In Fig. 8 a modified embodiment of the invention is shown in which the frame 37 is pivotally supported on trunnions as indicated at 38, by means of a pair of arms 39, one on each side of the frame, secured to a suitable wall surface. A pair of stop members 39' is secured to frame 37 and each member 39' projects beyond the frame far enough to engage arm 39 to limit the tilting motion of the frame. The garment carrier is shown in dotted lines in its rearmost position. In this position the center of gravity of the garment carrier is to the rear of the pivot 38, and the front end of the frame is tilted upwardly to an extent sufficient to keep the garment hanger from rolling forwardly because of its own weight. When the garment hanger is pulled forwardly past the pivot 38 the center of gravity is shifted forwardly of the pivot so that the front end of the frame is tilted downwardly, and the garment hanger will roll forwardly as in the other embodiments. The garment carrier can be made to roll forwardly by merely pulling down on the forward end of the frame. It is returned to the rearmost position either by being pushed there or by elevating the forward end of the frame and permitting it to roll back.

In Fig. 9 another modification of the invention is shown: The frame 40 is pivotally supported by a pair of arms 41, one on each side of the frame, projecting forwardly from a base 42 secured to a wall surface. Base 42 is provided with a socket-like recess 43 into which one leg 44 of a rocker arm 51 fits. The other leg 45 of the rocker arm is pivotally secured to one end of a lever 46 by a pin, as indicated at 47. Lever 46 is loosely secured to frame 40 by means of a plurality of straps or loops 48, and is provided with a handle 49 by which it may be manipulated. When the lever is pulled forwardly the rocker arm, which is pivoted to the frame, as indicated at 50, is rotated slightly about its pivot to raise the rear end of the frame so that the garment carrier will glide forwardly to its foremost position. Lever 46 is pushed rearwardly to raise the front end of frame 40 when the garment carrier is to be moved to its rearmost position. In this position, as in the case of the embodiment of Fig. 8, the center of gravity of the carrier is to the rear of the pivotal connections of arms 41 to the frame; and the carrier will remain in this rearmost position until the frame is tilted downwardly as described.

Although I have described some preferred embodiments of my invention in considerable detail, it will be understood that the description is intended to be illustrative, rather than restrictive, as many details may be modified or changed without departing from the spirit or scope of the invention. Accordingly, I do not desire to be restricted to the exact structure described.

I claim:

1. A display rack comprising a frame having a pair of longitudinal frame members inclined downwardly towards the front of said frame; a pair of cross members having rollers riding on said longitudinal frame members, a plate secured to said cross members and movable therewith, said plate supporting a depending shaft

to which a garment carrier is rigidly secured, latching means normally retaining said plate in its rearmost position, and wedge shaped members mounted on said longitudinal frame members to engage said rollers adjacent the front end of said frame, said wedge shaped members having their thicker ends closest to the front end of said frame to arrest the forward movement of said plate as it approaches the front end of said frame after said latching means is released.

2. A display rack comprising a rectangular frame having two longitudinal members inclined downwardly in its forward direction, a pair of cross members supporting a plate within said frame, said cross members being provided at their ends with rollers engaging said longitudinal members, interengaging latching means on one of 15 said cross members and said frame to hold said plate in its rearmost position, a shaft having its upper end projecting through said plate, a pin projecting transversely through said shaft and having its ends engaging said plate to rotatably support said shaft, means to disengage 20 said latching means, whereby said plate will move forwardly by gravity, and magnetic cushioning means stopping the forward movement of said plate after said latching means has been disengaged.

3. A display rack comprising a rectangular frame, a 25 rod of less length than said frame connected to said frame, a plate slidably mounted on said frame and adapted to be moved longitudinally thereof, a shaft rotatably supported by said plate, the top of said shaft being recessed to engage said rod to prevent rotation of said shaft until said plate is moved far enough to clear said shaft of said rod, and a garment carrier rigidly secured to said shaft.

4. A display rack comprising a rectangular frame having a front end and a rear end, a rod shorter than 30 35

said frame extending longitudinally thereof from the rear end of said frame, a plate mounted for longitudinal movement on said frame, a cam positioned above said plate, a shaft projecting through openings in said plate and cam, a pin projecting transversely through said shaft and engaging said cam to rotatably support said shaft, the top of said shaft being recessed to engage said rod to prevent rotation of said shaft except when said plate is near the front end of said frame, and a garment carrier rigidly secured to said shaft.
